Primary Examiner — Antoine Duval Davis(74) *Attorney, Agent, or Firm* — Crowell & Moring LLP(57) **CLAIM**

We claim the ornamental design for a configurable test instrument for power equipment, as shown and described.

DESCRIPTION

FIG. 1 is a top perspective view of a first embodiment of a configurable test instrument for power equipment.

FIG. 2 is a front elevation view of the first embodiment of the configurable test instrument for power equipment illustrated in FIG. 1.

FIG. 3 is a top perspective view of a second embodiment of a configurable test instrument for power equipment.

FIG. 4 is a front elevation view of the second embodiment of the configurable test instrument for power equipment illustrated in FIG. 3.

FIG. 5 is a rear elevation view of the embodiments of FIGS. 1-4.

FIG. 6 is a left side elevation view of the embodiments of FIGS. 1-4, the right side elevation view being a mirror image.

FIG. 7 is a top plan view of the embodiments of FIGS. 1-4; and,

FIG. 8 is a bottom plan view of the embodiments of FIGS. 1-4.
